SEQUENTIAL SWITCH RELEASE
MECHANISM

Orion S. Greeson, Elizabeth, N. J.

Application February 14, 1950, Serial No. 144,079

7 Claims. (Cl. 200—5)

1

This invention relates to control means for closing electrical circuits at different rates, and more particularly to a release mechanism for restoring a multiple switch unit with interdependent switching mechanism operating at different rates as described in the copending application, Serial No. 107,598, filed July 29, 1949, before the multiple switch unit has completed its entire cycle of functioning, the present application being a continuation in part of application Serial No. 107,598.

The primary object of this invention is to provide a release mechanism for instantly restoring the multiple switch unit to its normal or unactivated position from any other position in a cycle of functioning.

A further object of the invention is to provide a release mechanism for restoring certain elements of the switch to a normal position from a predetermined position in the cycle of functioning, while leaving other elements in an operated position.

Further and more specific objects of the invention will be readily apparent after an inspection of the above identified copending application, and these, together with the various ancillary objects of the invention which will become apparent as the following description proceeds, are attained by this switch release mechanism, a preferred embodiment of which has been illustrated in the accompanying drawings, by way of example only, wherein:

Figure 1 is a plan view of the multiple switch unit with the switch release mechanism in operative connection therewith, the multiple switch unit being shown in its initial or normal position;

Figure 2 is an end elevational view of the structure shown in Figure 1;

Figures 3 and 4 are partial plan views showing the switch release mechanism and the multiple switch in other operating positions;

Figure 5 is a perspective view of the invention;

Figure 6 is a perspective view of a bellcrank comprising one element of the invention;

Figure 7 is a perspective view of a lever adapted to be secured to a movable member of the multiple switch unit;

Figure 8 is a perspective view of a locking member adapted to be mounted on the base plate of the multiple switching unit; and

Figure 9 is a perspective view of the driving head which is connected to the driving or primary switch of the multiple switch unit.

With continuing reference to the accompany- 55

2

ing drawings, wherein like reference numerals designate similar parts throughout the various views, reference numeral 10 generally designates the multiple switch unit which, as illustrated in the drawings, comprises a base 12 bearing two uprights or posts 14 and 15 projecting therefrom, on which trip operating arms 16 and switch actuating arms 18 are mounted. The trip operating arm 16 is actuated by an electromagnet 20, operating device generally indicated as at 20, and both trip operating arms 16 and switch actuating arms 18 are coupled or connected by the motion-transmitting or locking device generally indicated at 21.

The trip operating arms 16 may be hinged to the vertical posts 14 and the switch actuating arms 18 may be hinged to the vertical posts 15, as indicated at 17, or they may consist of elastic arms fastened at one end to the vertical posts 14 and 15. The free ends of the trip operating arms 16 and 18 are movable and switch actuating arms are operated by the electromagnet 20 and the latching device 21, respectively. The initial position or normal position for the trip operating arm 16 is defined by the rod 40 which is actuated by the electromagnet 20 and the switch actuating arm 18 rests against block 77 supported on the base 12 near the free end of switch actuating arm 18. As can be readily seen from an inspection of the drawings, there are two sets of these multiple switch units shown.

The post 15 carries insulating blocks between which contact springs are arranged and connected to electrically actuated apparatus which the multiple switch is designed to control. These contact springs are generally indicated by reference numeral 24. The post 14 carries a simulating spring 25 for returning trip operating arm 16 to normal after operation. The electromagnet 20 for actuating the rod 40 which engages the trip operating arm 16 comprises a solenoid 34 mounted on the base plate 12 and provided with a core piece 35 carrying an armature 36. The armature, when attracted upon energization of the solenoid 34, pushes the rod 40 outwardly and thereby moves the trip operating arm 16 to an operative position, which, in turn, through motion-transmitting device 21, pushes the switch actuating arm 18 to an operative position actuating contact springs 27. As shown in the drawings, a plurality of multiple switching units are used. A rod 41 is connected to the switch actuating arm 18 for actuation of another trip operating arm 16 of an adjacent unit. Thus, the trip operating arm 16 of the adjacent unit is de-

pendent upon the actuation of the switch actuating arm 18 of the first unit for the actuation thereof and, accordingly, the change in rates of actuation of the electrical appliances to be controlled may be readily multiplied, since switch actuating arm 18 is actuated at a different rate than the trip operating arm 16.

The trip operating arms 16 carry a drive head 42. The latch devices 44 are carried by the switch actuating arms 18 and counter holding 10 and locking segments 50 are fixed on the base plate 12.

The latch devices 44 each includes a vertical latch plate 46 which is hinged by means of a pintle 47 to a cradle member 48 which is carried by and fastened to the switch actuating arm 18. The plate 46 carries an arm 51 which is fixedly attached thereto and projects therefrom. The arm 51 is arranged in a substantially horizontal plane and it supports at its end a guide pin 54. In addition, the latch plate carries two elastic pawls 55 and 56 which are preferably made from spring steel or the like. Each of the spring pawls 55 and 56 consists of a leaf spring with a bent end, the ends being at an angle to the remainder of the leaf spring and forming the raking edge of the pawls. Pawl 55 engages the driving head 42, while pawl 56 engages the locking segment 50. The pawls therefore determine the angular position of the latch plate 46 relative to the switch actuating arm 18. The latch plate 46 has a coil spring 57 attached thereto at one end. The other end of the coil spring 57 is attached to a pin 58 projecting from the secondary switch actuating arm 18. The spring 57, therefore, draws the hinged latch plate 46 inwardly.

The driving head 42 is shown more fully in Figure 9. This driving head substantially comprises a block which is U-shaped and which is provided with a yoke. A bore 59 passes through the yoke. Through the bore, a bolt 61 passes which is held in the cradle member 62 which is fixedly connected to the trip operating arm 16. At its end, the yoke of the block 42 is provided with a guide rod 53 passing through a slot in the guide post 43. By means of the guide rod 53 on the guide post 43, the drive head 42 is permitted only a substantially rectilinear movement. Additionally, the drive head 42 is provided with two legs 60 and 64 which are substantially parallel. One of the legs is provided with a step 63. The bent end of the pawl 55 may be applied against the step 63 if the latch plate 46 is in proper position. The second leg 64 of the drive head 42 is provided with a slanting end surface 65 running obliquely with respect to the axis of the U-shaped member 42. This leg is of shorter height than the yoke, but at its end is provided with a projection 70 of rhomboidal cross section. The rhomboid is formed on one side by the inclined surface 66 and on the other side by the parallel surface 67, both surfaces being vertical. Between these inclined surfaces, a vertical surface 68 is disposed which is a continuation of the inner vertical wall of the leg 64. The rhomboidal projection 70 and the adjacent contiguous surfaces of the leg 64 cooperate with the vertical guiding pin 54 on the horizontal arm 51 of the latch plate 46.

Referring now to Figure 8 in particular, it will be seen that the locking segment 50 is preferably an angular piece with a vertical flange 71 forming a support which is mounted on or

carried by the base plate 12. The vertical flange 71 carries a transversely projecting flange 72 which is cut in the manner as shown so as to form a locking tooth 75. The tooth 75 has a stepped surface 73 facing the secondary switch actuating arm 18 and substantially parallel thereto and an inclined surface 76 on the other side slanting at a comparatively acute angle away from the switch actuating arm 18 and forming an incline. The tooth 75 cooperates with the working end of the pawl 56. Obviously, the latch plate may be locked in this position when the pawl 56 is engaged behind the step 73 of the tooth 75 of the locking segment 50.

It is to be understood that an impulse of very short duration producing only a very small displacement of the trip operating arm 16 will operate the switch. Similarly, the push rod 40 may, of course, be operated in the same way by hand or by a mechanical device. The distance through which the push rod travels must only be equal to the distance between the pairs of switch contacts 27. This distance is chosen in accordance with the purpose which the switch is intended to serve in accordance with accepted principles of operation for such contacts.

When the switch is in its normal or initial position, the position of the various parts is that as shown in Figure 1 of the drawings. The two trip operating arms 16 and the two switch actuating arms 18 of each of the multiple switch units are substantially parallel and held in their position as defined by the push rod 40 and the block 71.

When in the normal position, the pawl 55 rests on the step 63 of the drive head 42 and is somewhat under tension. Pawl 56 rests on or is held above the incline 76 of the locking segment 50 and the spring pawl 56 is without tension. The guiding pin 54 on the arm 51 rests on the inner surface 68 of the rhomboidal projection 70 near the inner edge of the projection. The spring 57 is only very slightly tensioned. If the solenoid 34 is now energized, or if in any other way the push rod 40 transmits the first impulse to the trip operating arm, the latter is moved about its hinge and the drive head is moved forward toward the first secondary switch actuating arm 18. With the pawl resting against the step 63 of the drive head 42, the movement of the latter will move the latch plate 46 attached to the switch actuating arm 18, and the arm therefore closes a pair of the contacts 27. During this movement, the pawl 56 is riding on the incline 76 of the locking member 50. At the end of the forward stroke, the pawl 56 rides over the locking tooth 75 and is caught behind the step 73 of the locking tooth. The movement of the pawl 56 along the incline imparts to the latch plate 46 a tendency to move angularly and outwardly. This movement is, however, counteracted by the guide pin 54 pressing against the inner face 68 of the projection 70; therefore merely the pawl spring 56 is tensioned. In this position, which is the position assumed by the switch or switch actuating arm during the first impulse, switch actuating arm 18 has closed its associated contact springs 24. Furthermore, since the trip switch actuating arm 18 of the first switching unit has been actuated, the trip operating arm 16 of the second switch unit is actuated by movement of the push rod 41.

When the impulse ceases, push rod 40 and trip operating arm 16 return to their positions, the 75 drive head 42 moves back along with the trip

operating arm 16, while the second switch actuating arm 18 does not move back, as the pawl 56 has been caught behind the step 73 of the locking tooth 75 of locking member 50. Switch actuating arm 18, therefore, remains locked in its operative position. However, as the drive head 42 moves back, the relative positions of the latch plate 46, pawl 55, and drive head 42 now changes.

When the drive head 42 is moved back, the guide pin 54 loses contact with the inner wall 68 and moves outwardly along the side wall and finally passes the outermost edge. The tensioned and bent pawl 56 can now unbend and the latch plate 46 is now moved annularly and outwardly, tensioning the spring 57. The guide pin 54 is now in front of the inclined wall 65 of the projection 70 without touching it. Pawl 55 has been lifted away from step 63 and is no longer touching one of the two sections formed by the step in the leg 60. It is to be noted that while trip operating arm 16 is now at rest, the secondary switch actuating arm 18 is in its operative position closing its contact 27 and is locked in position indefinitely until a second operation occurs upon pawl 56 held against step 73 of tooth 75. Thus, the push rod 41 has actuated the trip operating arm 16 of the second switch unit. The position of the parts will, therefore, be such as those indicated in Figure 3.

Upon a further impulse, the relay 34 is energized and moves the push rod 40 forward again. This movement of the trip operating arm 16 also entails a movement of the driving head 42 toward the latch plate which falls on the guiding pin 54. The latter now rides on the projection 70 upon the movement of the drive head towards it, and is moved outwardly by the inclined outer face 65 of the rhomboidal section 70. A further angular movement of the latch plate 46 is thus produced, lifting pawl 56 out of the step 73 behind the locking tooth 75. Likewise, the pawl 55 is lifted further and now slides and rests on the upper face of the step 63 of leg 60. The second impulse therefore releases the secondary switch actuating arm 18 which is no longer held by locking member 50 and which, therefore, returns into its initial position, separating contacts 27 allied therewith. Thus, the primary trip operating arm 16 of the second multiple switch unit is released so that it may return to its rest position while the secondary switch actuating arm 18 of the second unit is held in an actuated position by its pawl 56 against the step 73 of the tooth 75, similar to that which held the secondary switch actuating arm of the first switch unit.

When the trip operating arm 16 of the first switch unit moves back, the guide pin 54 thereof rides on the inclined side 67 of the projection 70 and assumes the position for the first switch unit as shown in Figure 1, while the pawl 55 thereof rides along the upper face of the leg 60 and drops down in front of step 63, where it rests. Pawl 56 is held above the incline 76 or rests thereon.

It will be seen that a switch operation for the unit produces operational cycles for the two trip operating arms 16 and switch actuating arm 18 of the first unit which are progressing at different rates. The number of closing operations for trip operating arm 16 of the first unit with any given number of impulses, therefore, is exactly twice the number of closing operations performed by contacts 27 of the first unit which is in turn exactly twice the number of closing operations per-

formed by contacts 27 of the second unit. Upon the addition of additional switching units, the number of impulses is multiplied by two for each additional switch unit thereon applied. However, the multiple switching unit with this inter-dependent switching mechanism operating at different rates is so designed that it can be restored to its normal position only by running through the entire cycle of functioning. While this, in many cases, is entirely satisfactory, it is desirable to provide a releasing mechanism to provide means whereby the switch may be instantly restored to its normal position from any position in the cycle of functioning.

Two methods of effecting the release are involved, which are both employed and their effects coordinate, as demanded by the position of the members of the switch with which the mechanism is associated. The structure to effect these releasing actions comprises an extension 80, see Fig. 5 which is formed on the latching pawl 56 near the free end and extending downward toward the base 12. A post 82 extends upward from the base for each of the multiple switch units, and a bellcrank 84 is rotatably secured on top of this post by a rivet or other suitable means. The bellcrank moves in a plane parallel to the base 12 and the free end of one arm 86 of the bellcrank is under transverse flange 72. The other arm 88 of the bellcrank is forked as at 90, which forked end has a purpose to be henceforth explained.

An extension arm 92 is secured to each of the primary trip operating arms 16 and extends toward the front of the switch units. Pivotally connected by means of a rivet or the like on the free end of the extension arm 92 is a pull lever generally designated by reference numeral 94. This pull lever is best shown in Figure 7. Riveted or otherwise connected so as to form a part of the pull lever 94 is a resilient erecting lever 96 which has an offset portion forming a cam 98. Firmly fastened to a stud (not shown) on the extension arm 92 and a hole 100 in the lever 94 is a retractile spring 102 which tends to pull the pull lever 94 inwardly. This movement is limited by a shoulder 104 formed on the extension arm. Fastened to each of the secondary switch actuating arms 18 is an extension arm 106. This extends to the front of the switch units and the free end thereof is at the base of the erecting cam 98 so that when the secondary arm 18 is driven into its forward position and locked there and the primary arm travels to its backward position, the end of the extension arm 106 will ride up the slope of the cam 98 and thus erect the pull lever 94, i. e., it pushes the erecting lever outward until the hook 108 formed at one end of the pull lever 94 is positioned in front of the pin 110, which it is to engage.

As will be seen best in Figures 3 and 4, the pull lever 94 is moved for engagement with pin 110 by contact between cam surface 98 and the extension portion of the movable member 18. Actuation of the drawbar 112 effects movement of the pull lever which is connected to the trip operating arm 16 whereby the trip operating arm 16 and driving head 42 will move from the position of Figure 3 to the position of Figure 4, thereby effecting contact between the projection 70 and pin 54. By such action, the pawl 55 is disengaged from the shoulder 63.

A drawbar 112 is slidably mounted on the base 12 in front of the switch at right angles to the

primary and secondary trip arms and parallel to the base 12. The drawbar 112 is common to all of the switches in the series, that is, as shown in the drawings, the drawbar 112 is used for releasing the two multiple switch units shown. One end of the drawbar is secured to an electromagnet generally indicated at 114 which comprises an armature 116, pole pieces 118, core 120, coil 122, having terminals 124 for connection to a source of electrical power. A coil spring 126 is terminally secured to a stud 128 secured to the base 12 remote from the electromagnet 114 and to the drawbar 112 through an aperture 130 therein. The spring 126 continuously urges the drawbar 112 into its rearmost position, which is limited by shoulders 132. A pair of pins 134 are securely attached to the drawbar 112 for engagement by the forked portion 86 of the bellcrank 84. The drawbar 112 is slidably supported within a slot in a plate 136 mounted on the base 12.

When the electromagnet 114 is energized, the drawbar is pulled forward, actuating all bellcranks 84 and so effecting a release of all switches where the positions of the switch members demand a lifted release. All erected pull levers 94 will also be pulled forward, thus effecting a driven release on all switches where the positions of the switch members demand a driven release. These functions are possible because when the drawbar is pulled forward, the hooks 108 will engage the pins 110 to pull the primary trip operating arm 16 forward and the driving head 42 will engage release pin 54, thus unlatching the secondary arms 18. Additionally, when the drawbar 112 is pulled forward and if the latching pawl is in the notch 18, the end of the bellcrank arm will engage the extension 88 thereof and lift the latching pawl out of the notch.

Since the drawbar is common to all of the switches in a series of switches, as has been shown with two switches in the drawings, it will be readily seen that this releasing mechanism is common to all of the switches. The two important functions performed by the releasing mechanisms are to restore the switches in a series to their normal positions after the switching mission of the series is completed without the necessity of the switches going through useless operations which would be disturbing to the circuits of which the switch series are a part. The other function, of equal importance, is to alter the pattern of the cycle of operations of a switch or switch series. As covered in the foregoing, a cycle of functioning comprises a number of operations which are a power of two, that is, 4, 8, 16, and so on. The releasing mechanisms enable circuit arrangements to be made so that the switch series will run partly through the cycle, then be released to normal, and run through to the same or any point in the cycle. The pattern may be further altered by omitting the bellcrank 84 or pull lever 94 from certain switches in the series.

Since, from the foregoing, the construction and advantages of this form of switch release mechanism are readily apparent, further description is believed to be unnecessary.

However, since numerous modifications will readily occur to those skilled in the art after a consideration of the foregoing specification and accompanying drawings, it is not intended to limit the invention to the precise embodiment shown and described but all suitable equivalents and modifications of this base arrangement may be readily resorted to which fall within the scope of the appended claims.

Having described the invention, what is claimed as new is:

1. A multiple switch arrangement comprising a base having a primary switch and a secondary switch mounted thereon, a movable switch actuating member for each of said switches, switch contacts operated by said movable members, means for operating the movable member of each of said switches, a driving head on the operating means of each of the switches, each of said driving heads being provided with guiding means, latch release means and coupling means, stationary locking members carried by said base in juxtaposition to each of said driving heads, a coupling and latching driven member connected with the movable member of each of said switches, adapted to engage the stationary locking members, the driven member connected with the movable member of the primary switch engageable with the operating means of the secondary switch to transmit motion thereto whereby a first operation of the primary switch operating means moves both movable switch actuating members to a locked position, said driving head returning to its initial position and said coupling and latching driven member being disengaged from said driving head upon termination of said first operation, said driving head being actuatable upon a second operation of the primary switch operating means for movement into engagement with said coupling and latching driven member for effecting movement thereof from latching engagement with said stationary locking members.
2. A multiple switch arrangement comprising a base having a primary switch and a secondary switch mounted thereon, a movable switch actuating member for each of said switches, switch contacts operated by said movable members, means for operating the movable member of each of said switches, a driving head on the operating means of the primary switch, said driving head being provided with guiding means, latch release means and coupling means, stationary locking members carried by said base in juxtaposition to said driving head, a coupling and latching driven member connected with the movable member of each of said switches, adapted to engage the stationary locking members, the driven member connected with the movable member of the primary switch engageable with the operating means of the secondary switch to transmit motion thereto whereby a first operation of the primary switch operating means moves both movable switch actuating members to a locked position, said driving head returning to its initial position and one of the said coupling and latching driven members being disengaged from said driving head upon termination of said first operation, said driving head being actuatable upon a second operation of the primary switch operating means for movement into engagement with said one of the coupling and latching driven members for effecting movement thereof from latching engagement with said stationary locking members, and release means for selectively effecting release of said movable switch members of said primary and secondary switches prior to the completion of the operating cycle of the driving head.
3. A multiple switch arrangement comprising a base having a primary switch and a secondary switch mounted thereon, a movable switch actuating member for each of said switches, switch contacts operated by said movable members, means for operating the movable member of each of said switches, a driving head on the operating

means of the primary switch, said driving head being provided with guiding means, latch release means and coupling means, stationary locking members carried by said base in juxtaposition to said driving head, a coupling and latching driven member connected with the movable actuating member of each of said switches, adapted to engage the stationary locking members, the driven member connected with the movable member of the primary switch engageable with the operating means of the secondary switch to transmit motion thereto whereby a first operation of the primary switch operating means moves both movable switch members to a locked position, said driving head returning to its initial position and one of the said coupling and latching driven members being disengaged from said driving head upon termination of said first operation, said driving head being actuatable upon a second operation of the primary switch operating means for movement into engagement with said one of the coupling and latching driven members for effecting movement thereof from latching engagement with said stationary locking members, and release means for selectively effecting release of said movable actuating members carried by said primary and secondary switches prior to the completion of the operating cycle of the driving head, said release means including an electromagnet supported on said base, a drawbar reciprocably mounted on said base and actuatable by said electromagnet, said drawbar having pins secured thereto, pivotally mounted bellcranks on said base, either bellcrank having one end thereof engaging one of said pins for actuation thereby whereby said bellcrank upon pivoting movement selectively urges each coupling and latching driven member out of engagement with said stationary locking members.

4. A multiple switch arrangement comprising a base having a primary switch and a secondary switch mounted thereon, a movable switch actuating member for each of said switches, switch contacts operated by said movable members, means for operating the movable member of each of said switches, a driving head on the operating means of the primary switch, said driving head being provided with guiding means, latch release means and coupling means, stationary locking members carried by said base in juxtaposition to said driving head, a coupling and latching driven member connected with the movable member of each of said switches, adapted to engage the stationary locking members, the driven member connected with the movable member of the primary switch engageable with the operating means of the secondary switch to transmit motion thereto whereby a first operation of the primary switch operating means moves both movable switch members to a locked position, said driving head returning to its initial position and said coupling and latching driven member being disengaged from said driving head upon termination of said first operation, said driving head being actuatable upon a second operation of the primary switch operating means for movement into engagement with one of the said coupling and latching driven members for effecting movement thereof from latching engagement with said one of the stationary locking members, and release means for selectively effecting release of said movable switch members carried by said primary and secondary switches prior to the completion of the operating cycle of the driving head, said release means including an electro-

magnet supported on said base, a drawbar reciprocably mounted on said base and actuatable by said electromagnet, said drawbar having pins secured thereto, pivotally mounted bellcranks on said base, each bellcrank having one end thereof engaging one of said pins for actuation thereby whereby said bellcrank upon pivoting movement selectively urges either coupling and latching driven member out of engagement with said stationary locking members, said release means further including a pull lever having a cam surface engageable with each movable member, said pull lever being carried by the means for operating the movable members.

15 5. A multiple switch arrangement comprising
a base having a primary switch and a secondary
switch mounted thereon, a movable switch ac-
tuating member for each of said switches, switch
contacts operated by said movable members, first
20 means carried by said base for operating the
movable switch actuating member of the primary
switch, second means carried by said base for
operating the movable switch actuating member
of said secondary switch, said second means being
25 connected for movement with the movable mem-
ber of the primary switch, third means for oper-
ating the first means, said first and second means
each including trip operating arms pivotally
carried by said base, and drive heads reciprocably
30 supported by said base and pivotally connected
to each of said trip operating arms, each driving
head being provided with latch release means,
stationary locking members carried by said base
in juxtaposition to said driving heads, a coupling
35 and latching driven member connected with the
movable switch actuating member of each of said
switches adapted to engage the respective sta-
tionary locking members, a first operation of
the primary switch upon actuation of said third
40 means effecting movement of both movable
switch actuating members to a locked position,
the driving head of the primary switch return-
ing to its initial position and said coupling and
latching driven member of the primary switch
45 being disengaged from the driving head cooperat-
ing therewith upon termination of said first oper-
ation, said driving head of the primary switch
being actuatable upon a second operation of said
third means for movement into engagement with
50 said coupling and latching driven member of the
primary switch for effecting movement thereof
from latching engagement with the stationary
locking member of the primary switch, thereby
releasing the driving head of the secondary
switch for movement to its initial position.

65 6. A multiple switch arrangement comprising a base having a primary switch and a secondary switch mounted thereon, a movable switch actuating member for each of said switches, switch contacts operated by said movable members, first means carried by said base for operating the movable member of the primary switch, second means carried by said base for operating the movable member of said secondary switch, said second means being connected for movement 60 with the movable actuating member of the primary switch, third means for operating the first means, said first and second means each including trip operating arms pivotally carried by said base, and drive heads reciprocably supported by 65 said base and pivotally connected to each of said trip arms, each driving head being provided with latch release means, stationary locking members carried by said base in juxtaposition to said driving heads, a coupling and latching driven member connected with the movable actuating mem- 70 ber, and a means for returning the coupling and latching driven member to its initial position.

75

11

ber of each of said switches adapted to engage the respective stationary locking members, a first operation of the primary switch upon actuation of said third means effecting movement of both movable switch actuating members to a locked position, the driving head of the primary switch returning to its initial position and said coupling and latching driven member of the primary switch being disengaged from the driving head cooperating therewith upon termination of said first operation, said driving head of the primary switch being actuatable upon a second operation of said third means for movement into engagement with said coupling and latching driven member of the primary switch for effecting movement thereof from latching engagement with the stationary locking member of the primary switch, thereby releasing the driving head of the secondary switch for movement to its initial position, a still further operation of said third means effecting movement of the driving head of the secondary switch into engagement with said coupling and latching driven member of the secondary switch for effecting movement thereof from latching engagement with the stationary locking member of the secondary switch thereby opening the contacts made in the secondary switch.

7. A multiple switch arrangement comprising a base having a primary switch and a secondary switch mounted thereon, a movable switch actuating member for each of said switches, switch contacts operated by said movable members, first means carried by said base for operating the movable member of the primary switch, second means carried by said base for operating the movable member of said secondary switch, said second means being connected for movement with the movable actuating member of the primary switch, third means for operating the first means, said first and second means each including trip arms pivotally carried by said base,

12

and drive heads reciprocably supported by said base and pivotally connected to each of said trip arms, each driving head being provided with latch release means, stationary locking members carried by said base in juxtaposition to said driving heads, a coupling and latching driven member connected with the movable member of each of said switches adapted to engage the respective stationary locking members, a first operation of the primary switch upon actuation of said third means effecting movement of both movable switch actuating members to a locked position, the driving head of the primary switch returning to its initial position and said coupling and latching driven member of the primary switch being disengaged from the driving head cooperating therewith upon termination of said first operation, said driving head of the primary switch being actuatable upon a second operation of said third means for movement into engagement with said coupling and latching driven member of the primary switch for effecting movement thereof from latching engagement with the stationary locking member of the primary switch, thereby releasing the driving head of the secondary switch for movement to its initial position, and release means on said base for selectively effecting release of the interlocked movable members prior to the completion of the operating cycle of the driving heads.
